UNITED STATES PATENT OFFICE.

SUN R. STILL, OF HOT SPRINGS, ARKANSAS.

RAILWAY-TIE AND CLAMP.

1,097,373.

Specification of Letters Patent. Patented May 19, 1914.

Application filed February 18, 1914. Serial No. 819,431.

To all whom it may concern:

Be it known that I, SUN R. STILL, a citizen of the United States of America, residing at Hot Springs, in the county of Garland and State of Arkansas, have invented 5 certain new and useful Improvements in Railway-Ties and Clamps, of which the following is a specification.

This invention relates to a combined rail-way tie and clamp and it has for its object, 10 to provide an improved article of this nature constructed in such manner that the rail will be securely clamped to the tie by the placing in position of a single wedging element.

15 Another object of the invention is to simplify and cheapen the construction of an article of this nature.

Further objects and advantages of the invention will be set forth in the detailed description which now follows.

20 In the accompanying drawing, Figure 1 is a perspective view of a part of a railway track constructed in accordance with the invention, and Fig. 2 is a transverse sectional view therethrough.

Like numerals designate corresponding parts in both of the figures of the drawing.

Referring to the drawing the numerals 5 designate the rails. These rails are of substantially 25 X shape in cross section so that they comprise a wedge shape base and tread portion 6 and 7. Ties 8 are provided with dovetailed recesses 9 within which the base portions of the rails are seated and said base 30 portions are wedged into said recesses by wedges 10 which wedges are held against movement after they have been driven into position by set screws or like fastening devices 11 threaded into the overhanging portion 12 of the tie. As is best illustrated in 35 Fig. 1 the wedges 10 taper in two directions, that is they taper from end to end and also from the bottom to the top. The tapering of these wedges from end to end causes them 40 when they are driven home, to clench the base portions of the rail against the inner sides of the dovetailed recesses 9 and the tapering of these wedges from top to bottom causes them to act against the abutting face 45 of the base portion of the rail to force the rail firmly down against the bottom of the dovetailed recesses 9. The ties 8 are preferably 50 made of steel and they provide means not only for supporting the rail but they provide means for clamping the rail base 55

and for spacing the rails the proper distance apart. The rails are firmly seated in comparatively deep recesses of the ties and it is manifestly impossible for the rails to spread. It is therefore apparent that the 60 use of this device will prevent many of the serious railway accidents that have heretofore occurred because of the spreading of the rails. Furthermore the structure herein shown and described is a very cheap and 65 economical one.

While the elements shown and described are well adapted to serve the purposes for which they are intended, it is to be understood that the invention is not limited to the 70 precise construction set forth, but includes within its purview such changes as may be made within the scope of the appended claims.

Having described my invention, what I 75 claim is:

1. In a railroad track construction the combination with rails of substantial X shape in cross section to thereby provide the tread and base portion united at substantially 80 the vertical center of the rail, of ties having recesses formed therein for the reception of said rail, said recesses being of substantially half the depth of the rail, vertically considered, said recesses having overhanging inner walls which lie flush against the base portion of the rail from the bottom thereof to the vertical center of the rail the opposite side walls of said recesses being 85 likewise undercut but spaced from the base 90 portions of the rails, wedges seated between the base portions of the rails and said undercut walls, said wedges tapering in two directions the inner faces being of such shape as to lie flat against the base portions 95 of the rail from the bottom of the rail to substantially the vertical center thereof.

2. In a railroad track construction the combination with rails of substantial X shape in cross section to thereby provide the tread and base portion united at substantially 100 the vertical center of the rail, of ties having recesses formed therein for the reception of said rail, said recesses being of substantially half the depth of the rail, vertically considered, said recesses having overhanging inner walls which lie flush against the base portion of the rail from the bottom thereof to the vertical center of the rail the opposite side walls of said recesses being 105 110

likewise undercut but spaced from the base portions of the rails, wedges seated between the base portions of the rails and said undercut walls, said wedges tapering in two directions the inner faces being of such shape as to lie flat against the base portions of the rail from the bottom of the rail to substantially the vertical center thereof, the width of said base being such in proportion

to the width of the recess that the rails may 10 be rocked out of said recesses.

In testimony whereof I affix my signature in presence of two witnesses.

SUN R. STILL.
